UNITED STATES PATENT OFFICE.

CHARLES E. GODLEY, OF DETROIT, MICHIGAN, ASSIGNEE, BY MESNE ASSIGNMENTS,
TO C. M. HALL LAMP COMPANY, A CORPORATION OF WISCONSIN.

COMBINATION REAR LIGHT FOR VEHICLES.

Application filed July 25, 1924. Serial No. 728,085.

My invention relates to compartmental lamps in which separate lamp bulbs are employed for lighting lamp front portions respectively opposite different compartments 5 of the lamp casing. Lamps of this general class are commonly employed as rear lamps for vehicles to afford the usual tail light indication from a light in one compartment of the lamp casing, and to afford an occasional 10 stop-signal indication from a light in another compartment.

For such purposes, my invention provides a novel construction and arrangement of the means for partitioning the casing into 15 two compartments, for supporting two lamp bulbs so that their filaments will be disposed respectively within the two compartments, and for making separate circuit connections to the usual axial terminals of the 20 two lamp bulbs. More particularly, my invention provides a construction for this purpose in which the partitioning means have rearwardly diverging portions upon which the sockets for the two lamps are mounted, 25 in which the diverging of the said portions affords a space adjacent to the back of the casing for housing a pair of resilient conducting elements which respectively engage the said lamp terminals, and in which the 30 back of the casing has a socket adapted to receive a wire-terminal plug so as to support the latter in proper conducting relation to the said conducting elements.

Furthermore, my invention provides a 35 compartmental lamp construction in which the rearwardly diverging portions of the partitioning means have feet secured to the back of the casing so as to support the partitioning means and the lamp sockets 40 carried by the latter. It also provides a construction in which a single insulator affords the mounting for the two resilient conducting elements which respectively engage the axial terminals of the two lamp 45 bulbs, and in which these conducting elements extend respectively in opposite directions from the main portion of the partition and from the axis of the said insulator. Still further and also more detailed objects 50 will appear from the following specification and from the accompanying drawings, in which

Fig. 1 is a front view of a combined tail and stop lamp for use on the rear of a vehicle, embodying my invention.

Fig. 2 is an enlarged front view of the same lamp with the lens-carrying cover and the lamp bulbs detached.

Fig. 3 is a central and vertical section taken longitudinally through the same lamp, 60 or along the line 3—3 of Fig. 2.

Fig. 4 is a rear view of the partitioning member, including the insulator and the pair of conducting members carried by this partitioning member.

Fig. 5 is a perspective view showing the insulator and the two conducting members fastened thereto, before this assembly is secured to the partitioning member.

Fig. 6 is a central and vertical section 70 similar to that of Fig. 3, but with the lamp front omitted, showing another embodiment of my invention, namely one in which the two conducting members which respectively engage the axial terminals of the two lamp 75 bulbs are mounted on separate insulators respectively secured to rearwardly diverging portions of the partitioning member, and in which each of these conducting members comprises two spring fingers.

Fig. 7 is a front elevation of the two resilient conductors of the embodiment of Fig. 6.

Fig. 8 is a perspective view of one of these 85 two-part resilient conductors.

Referring first to the embodiment of Figs. 1 to 5 inclusive, this shows a lamp in which the casing has a substantially cylindrical lateral wall 1 integral with a vertical and substantially flat back 2. This cylindrical 90 wall is flared out at its forward or mouth end to receive a lens front including an upper glass portion 3 bearing the signal indication "Stop" and a lower light-concentrating portion 4, both of which lens portions are here shown as carried by a correspondingly apertured cover plate 5 which has a peripheral flange telescoped over the mouth of the casing. The casing also has the lower portion of its wall 1 cut away to afford 100 an opening closed by a curved glass pane 6 which is held in position by clips 7 and through which light from the lower lamp bulb can issue downwardly for lighting the license plate which is usually disposed below 105 the lamp.

To light the said lower lens portions and window pane, I provide within the casing a pair of lamp bulbs 7 and 8 of the usual type having metal collars 9 and 10 respectively 110

socketed in tubular sockets 11 and 12, each of these sockets having bayonet slots 42 receiving and interlocking with the usual laterally projecting pins 13 upon the lamp base socketed by it.

To support these sockets and to divide the casing into compartments respectively opposite the lens front portions 3 and 4, I provide a partitioning member which has a forward portion 14 extending substantially to the said lens front and which has a pair of rearwardly diverging webs 15 and 16. One of these webs, namely the web 16 is here shown as integral with the forward and generally horizontal partition portion 14, while the other web 15 is secured to this portion 14 by rivets 17. Thus arranged, the rearwardly diverging webs 15 and 16 afford a space adjacent to the back of the casing for housing the conducting elements hereinafter mentioned, and in the present embodiment this space is extended forwardly of the casing so as to afford additional room for housing an insulator 18 and the portions of the 25 conducting members which are fastened to that insulator.

This insulator in the illustrated embodiment comprises a flat plate 18 having a pair of perforations 19 through which the rivets 30 17 extend, so that these rivets serve for simultaneously securing the separate web 15 to the main partition portion 14 which carries the other web, and also for securing the insulating plate rigidly to the partitioning 35 member which includes both webs. Mounted on the insulating plate 18 are a pair of conducting members, which members are here shown as having feet 20 bearing flatwise against opposite sides of the insulating 40 plate 18 and respectively secured to the latter by rivets 21 and 22. Each of these conducting members also has a resilient finger overhanging the rear edge of the insulating plate and these insulating fingers 23 and 24 45 extend transversely of the insulator 18 and in opposite direction from each other, thereby enabling these resilient fingers to respectively engage the axial terminals 25 and 26 of the two lamps. With this in mind, the 50 sockets 11 and 12 are open at the back so that resilient fingers or conducting elements 23 and 24 can readily engage the said axial lamp terminals without touching the adjacent webs of the partitioning member.

To afford the needed circuit connections to the conducting members of which the said resilient fingers form a part, I provide the back of the casing with a tubular socket 47 which opens into the said space between the 55 two diverging webs, this socket having bayonet slots 56 for receiving the usual lateral pins 27 on a wire terminal plug. This plug is here shown as including a pair of wire terminals 28 which are both mounted in an insulator 29 and which are respectively con-

nected by spring pressed plungers 30 and 31 to the resilient fingers 23 and 24.

To support the partitioning member in proper position for this purpose, I desirably provide each of the two diverging webs of 70 the partitioning member with a foot engaging the back of the casing, these feet being here shown as 32 and 33 and each of these feet being secured to the back of the casing by a screw 34. I also desirably provide the 75 partitioning member at its forward edge with a pair of ears 35 adapted to engage the back of the lamp front and threaded to receive screws 36 extending through the said front to fasten the latter in its normal closure position.

With the lamp thus constructed, and with the forward edge of the partitioning member shaped so as to be opposite the portion of the lamp front between the lens parts 85 3 and 4 (or substantially along the dotted line 37 of Fig. 1), it will be evident that the forward partitioning portion 14 together with the downwardly and rearwardly directed web portion 16 form a top for the 90 lower compartment of the casing so that light from the lower lamp bulb 8 will not reach the upper compartment. It will also be evident that the inclination of the diverging webs permits each lamp to have its 95 filament disposed at some distance from the lamp front while employing a relatively short casing. So also, the divergence of the webs affords the needed room for portions of the conducting member which carry the 100 current respectively from the two wire terminals to the axial lamp terminals, thereby permitting an unusually compact lamp construction. By disposing the plug socket 25 substantially in axial alignment with the 105 main portion of the partitioning member and with the insulator 18, I provide an assembly which will readily adapt itself for use with standard types of two-wire attaching plugs, and by employing the widely spaced feet of the rearwardly diverging webs as supports for the partitioning member, I can readily secure an unusually firm supporting of the latter so as to permit the 110 use of relatively thin material for its construction.

However, while I have heretofore described my invention in an embodiment in which one of the diverging webs is integral with the forward portion of the partitioning member and in which both of the resilient conducting members are carried by a single insulating plate secured to the partitioning member, I do not wish to be limited to these or other details of the construction and 120 arrangement thus disclosed. Obviously, many modifications might be made without departing either from the spirit of my invention or from the appended claims.

For example, Fig. 6 shows an embodiment 130

in which the two diverging webs 38 and 39 are integral with each other and are formed of a separate piece of metal from the forward horizontal partition portion 40. They 5 also show a construction in which each of the two resilient conducting members is composed of two spring fingers 43 and 44 which respectively engage one axial lamp bulb terminal and one plug terminal. In this case, 10 the two-fingered resilient conducting members are secured respectively to the two diverging webs of the partitioning member, each being insulated from the corresponding web, as for example by insulators 45 and 46. 15 Each of the said conducting members has one finger 44 laterally offset from the other, so that these two fingers extend freely alongside each other in engaging the plug terminals which are spaced laterally of the 20 lamp, while the other two fingers 43 have their medial lines in the medial plane of the two lamp bulbs and each engage a terminal of one of these bulbs. 25 With either embodiment, the diverging webs of the partitioning member cooperate with the back of the casing for affording a rear chamber in which the base terminals of the two lamp bulbs and the forward ends 30 of the circuit terminals are exposed, and this chamber also houses the two conducting members.

I claim as my invention:—

1. In a lamp, a forwardly open casing, a partition dividing the casing into two compartments and having a pair of webs extending in diverging relation up to the back of the casing, means upon each web for holding a lamp bulb with the base thereof extending through that web into the space between the diverging webs and the back of the casing, a pair of circuit terminal members, means for supporting the said members from the casing and for insulating the said members both from each other and from the casing, two resilient conducting elements respectively connecting the said members with the axial terminals of the lamp bulbs, and means for supporting the said elements from the partition and for insulating the said elements from each other and from the partition.

2. A lamp as per claim 1, in which each web has a foot portion secured to the back of the casing.

3. In a lamp, a forwardly open casing, a partition dividing the casing into two compartments and having a pair of webs diverging from each other toward the back of the casing, means upon each web for holding a lamp bulb with the base thereof extending through that web into the space between the diverging webs and the back of the casing, a plug socket mounted on the back of the casing and opening into the said space, an insulator carried by the socket, a pair of rel-

atively insulated circuit terminal members carried by the insulator and projecting forwardly into the casing, two resilient conducting members disposed within the casing and respectively connecting the circuit terminal members with the axial terminals of the lamp bulbs, and means for supporting the said members from the partition and for insulating the said members from each other and from the partition. 75

4. In a lamp, a forwardly open casing, a partition dividing the casing into two compartments and having a pair of webs diverging from each other toward the back of the casing, means upon each web for holding a lamp bulb with the base thereof extending through that web into the space between the diverging webs and the back of the casing; two resilient conducting members respectively engaging the axial terminals of the two lamp bulbs, means for supporting the said members within the said space and for insulating the said members from each other, and detachable means carried by the back of the casing for affording two relatively insulated circuit connections respectively to the two conducting members. 80

5. In a lamp, a forwardly open casing, a partition dividing the casing into two compartments and having a pair of webs diverging from each other toward the back of the casing, means upon each web for holding a lamp bulb with the base thereof extending through that web into the space between the diverging webs and the back of the casing, a pair of resilient conducting members disposed in the said space and each having a portion engaging a terminal of one lamp bulb, the said members having other portions disposed adjacent to each other and to the back of the casing, means mounting said members on and insulating them from said partition, and means carried by the back of the casing for affording circuit connections respectively to the said conducting members 100 105 at the said other portions. 110

6. A lamp as per claim 1, including an insulator on which both of the said conducting elements are mounted, the insulator having its axis substantially in the plane from which the webs of the partition diverge and the conducting elements having lamp-bulb-engaging portions extending in respectively opposite directions transversely of the said plane. 115

7. A lamp as per claim 1, including an insulating plate secured flatwise to the partition, and extending into the said space between the diverging webs, the said conducting elements being mounted upon the insulat- 120 125 ing plate.

8. A lamp as per claim 1, in which one of the webs is integral with the partition and the other web has a portion secured to the partition, each web having a foot secured to 130

- the back of the casing for supporting the partition.
9. In a lamp, a forwardly open casing, a partitioning member mounted in the casing including means providing a chamber adjacent to the back of the casing and dividing the part of the casing forwardly of the said chamber into upper and lower compartments, a pair of circuit terminals extending through the back of the casing into the said chamber, means for supporting the said circuit terminals from the back of the casing and for insulating the circuit terminals both from each other and from the back of the casing, means upon the partitioning member for supporting two lamp bulbs with their bulbs respectively in the said upper and lower compartments and with the base terminals both disposed in the said chamber, two resilient conducting members both disposed in the said chamber and each connecting one of the circuit terminals with one of the said base terminals, and means carried by the partitioning member for supporting the said conducting members and for insulating the conducting members both from each other and from the partitioning member.
10. A lamp construction as per claim 9, in which each of the conducting members includes a rigidly supported portion and a pair of resilient arms respectively engaging one of the circuit terminals and one of the said base terminals.

Signed at Detroit, Michigan, July 17th, 1924.

CHARLES E. GODLEY.
